MATERIAL HANDLING VEHICLE

Frank Cartlidge, Chicago, Ill., assignor to Goodman Manufacturing Company, Chicago, Ill., a corporation of Illinois

Application November 6, 1943, Serial No. 509,187

5 Claims. (Cl. 214—83)

This invention relates to improvements in material handling vehicles, and more particularly to rubber-tired mine cars commonly known as shuttle cars or buggies, used for transporting coal from a loading machine at the working face of a mine to a discharge station such as a mine car or a belt conveyer in the main haulage entry. Shuttle cars of this type usually consist of a self-propelled car or a trailer car having a coal carrying compartment and an endless flight conveyer forming the bottom thereof. Such cars are usually loaded at one end from the overhanging boom of a loading machine and the bottom conveyer of the car is intermittently moved towards the opposite or discharge end of the car so as to distribute the load evenly over the full length of the coal compartment. After the car is fully loaded it is driven to its discharge station, where the bottom conveyer is again operated to unload the entire contents of the car from its discharge end.

One of the difficulties heretofore encountered with cars of this type is that of spillage of material at the discharge end of the coal compartment, either while the car is being loaded or while it is being guided or driven to the discharge station. To avoid such spillage it has been proposed to provide movable gates of various kinds arranged to close the discharge end of the compartment until the car is to be unloaded. One form of end gate proposed for this purpose is hinged or pivoted on a transverse axis near the top of the compartment so as to be swung upwardly and away from the discharge opening when the coal is being unloaded. Gates of this kind are not entirely satisfactory, however, because fine coal and coal dust are likely to spill from along the bottom edge of the gate in the space left for outward passage of the upright flights or cross bars of the endless conveyer. It will be understood that this conveyer is often operated while the gate is closed so as to distribute the load evenly over the full length of the coal compartment, as previously described.

The object of the present invention is to overcome the difficulties above outlined by providing a positive closure means along the bottom edge of the end gate, which will permit the flights of the conveyer to pass beneath the end gate without interference but will keep the space for such passage closed against spillage of fine coal and dust at all times.

In carrying out my invention I provide an improved form or shape of flight or cross bar and also provide further the end gate with a slidab

5 spring pressed plate member so disposed with respect to the moving conveyer flight and the adjacent bottom of the discharge passage as to maintain a substantially tight seal against spillage without interfering with the normal movement of the conveyer.

The invention may best be understood with reference to the accompanying drawing in which:

Figure 1 is a fragmentary side view showing the 10 discharge end of a shuttle car to which the invention is applied;

Figure 2 is an enlarged view showing details of the end gate in closed position, and with the stripper plate in lowered position;

15 Figure 3 is a view similar to Figure 2, but showing the stripper plate raised by engagement with a conveyer flight; and

Figure 4 is an end view of the car, showing the stripper plate lowered at the left side and raised 20 at the right side of the figure.

Referring now to details of the embodiment of the invention illustrated in the drawing, the end gate structure is shown as applied to the front or discharge end of a shuttle car. As usual, the 25 shuttle car has a frame 10 provided with a pair of laterally spaced side walls 11, 11 and a floor plate 12 which defines an elongated material compartment 13. An endless flight conveyer 14 has its upper reach movable longitudinally along the floor plate 12 to discharge the coal from one 30 end of the compartment. The conveyer consists of a pair of laterally spaced chains 15, 15, having a plurality of flights or bars 16 extending therebetween at spaced intervals. The conveyer 35 chains 15, 15 are trained over sprockets 17, 17 on a shaft 18 at the front end of the car, and the lower reach of the conveyer extends rearwardly as usual, beneath the floor plate 12. The conveyer may be driven by power in any suitable manner, as by a motor 20 disposed on the outer side of one of the upright walls 11. A plurality of supporting wheels 21 have suitable mechanism associated therewith for driving and steering the car as usual.

45 The end gate structure forming the subject matter of the present invention is indicated generally at 25, and consists of a plate 26 pivotally mounted along its upper edge between the upper margins of the side walls 11, 11. In the form 50 shown herein, the hinged mounting consists of a transverse shaft 27, having its ends supported on the walls 11, 11 to provide a pivotal support for the end plate 26.

The body of the end plate 26 is preferably bent 55 outwardly intermediate its top and bottom edges,

as shown in Figures 2 and 3, so as to form upper and lower portions 28 and 29 disposed at an obtuse angle to each other.

A stripper plate 30 is slidably mounted along the bottom edge of the lower gate portion 29 so as to form a movable extension of the latter. In the form shown, said stripper plate is guided for movement along the outer face of the lower gate portion 29 by a strap 31 fixed at its opposite ends to the lateral margins of said gate portion. A pair of slotted guide extensions 311 are formed integral with the stripper plate, and are slidably engaged by bolts 312, 312, on the outer face of the end gate, as shown in Figure 4.

A pair of springs 32, 32 are suitably mounted on said lower gate portion above the stripper plate 30 in position to urge the latter downwardly toward the conveyer 14. The springs 32 may be housed in cylindrical casings 33 suitably secured to the rear face of the gate. Plungers 34, formed integral with the stripper plate, extend into the lower ends of the casings 33, and have heads 36 abutting the lower ends of the springs. Stops 37, 37, herein mounted on the lower ends of spring housings 33, are provided to engage the heads 36 of plungers 34, to limit the extensible movement of the stripper plate.

In order to cooperate in the stripping action of the extensible plate 30, the transverse flights 16 of the endless conveyer are each formed of a strip of metal bent longitudinally in an inverted V-shape, as shown in Figures 2 and 3. The advancing inclined faces 38 of said flights are arranged at a suitable angle to engage and raise the stripper plate against the compression of the springs 32, 32 as each flight is moved beneath the lower edge of the end gate. The retreating inclined faces 39 of said flights are preferably disposed at an angle slightly greater than that of the stripper plate 30 when the gate is in closed position, as shown in Figure 2. The arrangement just described is such that all loose coal or coal dust will be stripped from each of the conveyer flights as it passes under the end gate, thereby maintaining an effective seal against spillage along the bottom of the gate while the latter is closed. Moreover, the angular relation of the stripper plate and the retreating faces 39 of the flights is such as to cause a relatively gradual extension of said plate after it has passed the peak of the flight, so as to avoid a sudden drop of said plate.

Suitable locking means is also provided for the end gate, herein consisting of a pin 40 which is slidably extensible through a side wall 11 so as to be engaged at will with a lug 41 fixed on the shaft 27. Operation of said locking pin may be manually controlled by a hand lever 42 supported on the outer face of the side wall, as shown in Figure 4.

The use and operation of the end gate structure above described will now be understood by those familiar with the art. The end gate may be locked in its lowered or closed position while the car is being loaded. The bottom conveyer can be intermittently moved, as usual, to permit gradual loading of the car from its rear end to the front or discharge end, and the stripper plate will keep the coal from spilling along the bottom edge of the gate, both while the car is being loaded, and while it is being transported to its unloading station. The gate may then be unlocked and raised as indicated in dotted lines in Figure 1, to permit unloading of the car in the usual manner.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

- 10 1. I claim as my invention:
  1. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end,
  - 15 2. a stripper plate slidably mounted on said plate member for yieldable engagement with said bottom plate, and the flights of said conveyer being beveled to engage and lift said stripper plate, so said flights may pass thereunder and said stripper plate may strip material therefrom.
  - 20 3. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end,
  - 25 4. a stripper plate slidably mounted on said plate member for yieldable engagement with said bottom plate, and the flights of said conveyer being beveled to engage and lift said stripper plate, so said flights may pass thereunder and said stripper plate may strip material therefrom.
  - 30 5. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end, means selectively operable for holding said plate member in a closed position, a stripper plate slidably mounted on said plate member for engagement with said bottom plate, the flights of said conveyer being beveled to engage and lift said stripper plate, so said flights may pass thereunder and said stripper plate may strip material therefrom when said plate member is in a closed position, and means for yieldably engaging said stripper plate with said bottom plate and flights.
  - 35 6. In a vehicle for transporting loose material in mines underground, a wheel mounted material carrying compartment having an endless chain flight conveyer movable along a bottom plate thereof including a plurality of longitudinally spaced, vertically disposed flights for discharging material from one end of said compartment, an end gate structure normally closing the discharge opening of said compartment and including a plate member transversely pivoted to said compartment adjacent its upper end, said plate member being bent outwardly intermediate its top and bottom edges so as to form upper and lower portions disposed at an obtuse angle to each other, the lower end of said plate member being normally at an obtuse angle with respect to the conveyer and having a stripper plate slidably mounted thereon for yieldable engagement with said conveyer and said flights at an obtuse angle to the direction of travel thereof.
  - 40 7. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end, said plate member being bent outwardly intermediate its top and bottom edges so as to form upper and
- 45 8. In a vehicle for transporting loose material in mines underground, a wheel mounted material carrying compartment having an endless chain flight conveyer movable along a bottom plate thereof including a plurality of longitudinally spaced, vertically disposed flights for discharging material from one end of said compartment, an end gate structure normally closing the discharge opening of said compartment and including a plate member transversely pivoted to said compartment adjacent its upper end, said plate member being bent outwardly intermediate its top and bottom edges so as to form upper and
- 50 9. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end, said plate member being bent outwardly intermediate its top and bottom edges so as to form upper and
- 55 10. In a vehicle for transporting loose material in mines underground, a wheel mounted material carrying compartment having an endless chain flight conveyer movable along a bottom plate thereof including a plurality of longitudinally spaced, vertically disposed flights for discharging material from one end of said compartment, an end gate structure normally closing the discharge opening of said compartment and including a plate member transversely pivoted to said compartment adjacent its upper end, said plate member being bent outwardly intermediate its top and bottom edges so as to form upper and
- 60 11. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end, said plate member being bent outwardly intermediate its top and bottom edges so as to form upper and
- 65 12. In a vehicle for transporting loose material in mines underground, a wheel mounted material carrying compartment having an endless chain flight conveyer movable along a bottom plate thereof including a plurality of longitudinally spaced, vertically disposed flights for discharging material from one end of said compartment, an end gate structure normally closing the discharge opening of said compartment and including a plate member transversely pivoted to said compartment adjacent its upper end, said plate member being bent outwardly intermediate its top and bottom edges so as to form upper and
- 70 13. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and including a plate member transversely pivoted to said compartment adjacent its upper end, said plate member being bent outwardly intermediate its top and bottom edges so as to form upper and
- 75 14. In a vehicle for transporting loose material in mines underground, a wheel mounted material carrying compartment having an endless chain flight conveyer movable along a bottom plate thereof including a plurality of longitudinally spaced, vertically disposed flights for discharging material from one end of said compartment, an end gate structure normally closing the discharge opening of said compartment and including a plate member transversely pivoted to said compartment adjacent its upper end, said plate member being bent outwardly intermediate its top and bottom edges so as to form upper and

lower portions disposed at an obtuse angle to each other, the lower end of said plate member being at an obtuse angle with respect to the conveyer and having a stripper plate slidably mounted thereon for engagement with said conveyer at an obtuse angle to the direction of travel thereof, and means for yieldably engaging said stripper plate with said conveyer, to strip material therefrom as said conveyer passes thereby.

5. In a vehicle for transporting loose material in mines underground, a wheel mounted material carrying compartment having an endless chain flight conveyer movable along a bottom plate thereof for discharging material from one end thereof, an end gate structure normally closing the discharge opening of said compartment and

including a plate member transversely pivoted to said compartment adjacent its upper end, said plate member being bent outwardly intermediate its top and bottom edges so as to form upper and lower portions disposed at an obtuse angle to each other, the lower end of said plate member being at an obtuse angle with respect to the conveyer and having a stripper plate slidably mounted thereon for engagement with said conveyer at 10 an obtuse angle to the direction of travel thereof, the flights of said conveyer being beveled so as to engage and lift said stripper plate to permit said flights to pass thereby, and means for yieldably engaging said stripper plate with said bottom plate.

FRANK CARTLIDGE.
